UNITED STATES PATENT OFFICE.

WALTER E. BARNARD, OF STAMFORD, CONNECTICUT, ASSIGNOR TO UNDERWOOD TYPEWRITER COMPANY, OF NEW YORK, N. Y., A CORPORATION OF DELAWARE.

TYPEWRITING-MACHINE.

1,386,391.

Specification of Letters Patent.

Patented Aug. 2, 1921.

Application filed November 7, 1918. Serial No. 261,447.

To all whom it may concern:

Be it known that I, WALTER E. BARNARD, a citizen of the United States, residing in Stamford, in the county of Fairfield and State of Connecticut, have invented certain new and useful Improvements in Typewriting-Machines, of which the following is a specification.

This invention relates to typewriting machines, and more especially to the controlling of the ribbon mechanism in such machines. The invention is herein described as applied to an Underwood typewriting machine having a ribbon mechanism adapted to write in either of two colors, and also adapted to be made ineffective to permit stencils to be cut by the typewriter.

It is a feature of my improvements to be able to set the ribbon mechanism to one position or another at will, and to provide means which, when set to a certain position will remain in that position, and if temporarily moved to another position, for typing characters in a different color, or accidentally, as in cleaning the machine, will automatically return to the set position. The invention is herein shown as applied to the usual bichrome mechanism of the Underwood typewriting machine, which is so constructed that it may also be used for stencil cutting, and the connections are such, as herein disclosed, that the finger-piece which effects the setting may be positively set to the desired position, and yet have many of the advantages which would result from a yielding connection between the finger-piece and the ribbon mechanism.

Other features and advantages will hereinafter appear.

40 In the accompanying drawings,

Figure 1 is a sectional side view, showing part of an Underwood typewriting machine having the present invention applied thereto.

45 Fig. 2 is a skeleton perspective view, showing most of the parts of the present invention.

Fig. 3 is a dissected perspective view, showing the settable finger-piece and some 50 coöperating parts.

Fig. 4 is a face view from the rear of the parts shown in Fig. 3 set for writing black.

Fig. 5 is a view similar to Fig. 3, but showing the finger-piece moved away from

the position of Fig. 4 against the tension of 55 the spring, which tends to move it to the position of Fig. 4.

Fig. 6 is a view similar to Fig. 4, but showing the parts set for red printing.

Fig. 7 is a similar view, showing the parts 60 set for stencilizing.

In the Underwood typewriting machine, character keys 1, which are mounted on the front ends of key-levers 2, when depressed, carry down bell-cranks 3 to cause type-bars 65 4 to swing upwardly and rearwardly, so that types 5 on the latter will print against the front side of the platen 6 through the black stripe 7, or the red stripe 8, of the usual ribbon. The ribbon normally stands below the 70 printing point, and is raised to the printing point at the actuation of a character key, by means of a universal bar 9, which is adapted to be struck by heels 10 on the type-bars as the type-bars approach the platen, with the 75 result that the universal bar is carried rearwardly and lifts the usual ribbon carrier 11.

To enable the ribbon carrier to be thus lifted, the universal bar is provided with a flat portion 12, on which is mounted a housing 13 adapted to be shifted to the right or left, so that either the wall 14 or the wall 15 of the housing will engage the proper pin 16. When either wall of the housing engages its pin 16, it carries the pin rearwardly at the rearward movement of the universal bar when the type-bar rises, thus carrying rearwardly the upper end 17 of a pivoted ribbon vibrator 18 on which the pins 16 are fast, and which is pivotally attached to the ribbon carrier 11, with the result that the vibrator 18 will lift the ribbon to an extent depending on which wall of the housing engages a pin 16. To effect this, the pins 16 are set at different distances 85 from the pivot 19, about which the vibrator 18 turns, so that when the wall 15 engages its pin 16, it will give the vibrator 18 a small throw, because its pin 16 is the more distant from the pivot 19 than is the pin 16 100 which is adapted to be engaged by the wall 14. The construction is such that the housing 13 may occupy an intermediate position, in which position it engages neither of the pins 16, and thus moves idly backward and 105 forward with the universal bar.

In order to enable the typist to shift the housing 13 on the universal bar, the housing

is pivotally connected by means of a link 20 to a rock arm 21 fast on a rock shaft 22, extending through the front of the machine frame or casing 23, at which point the shaft 22 terminates in a finger-piece 24. The rocking of the rock shaft 22 will shift the housing 13 to any desired position. To effect this rocking, the shaft 22 is somewhat loosely journaled in a bracket 25 fast on a lug 26 of the segment in which the type-bars are journaled. To rock the rock shaft 22 in the bracket 25, the finger-piece 24 may be raised or lowered in a slot 27 of a bracket 28 which is fast to the usual front wall 29 of the casing of the typewriter. The raising or lowering of the finger-piece 24 is adapted to rock the shaft, because there is fast on the shaft 22 a fork 29^a engaging a pin 30 fast on one of the usual ribbon spool brackets 31, and since this pin 30 is to one side of the center of the shaft 22, moving the shaft up and down will rock the shaft around the pin 30 as a pivot, thereby rocking the rock arm 21 and sliding the housing 13 along the universal bar 9.

For the purpose of yieldingly holding the finger-piece 24 set in any desired position, the enlarged hub 32 of the finger-piece forms a releasable locking catch which is adapted to be set in any one of a plurality of openings 33, 34 or 35 in a plate or keeper 36 pivoted to the bracket 28 by a suitable screw 37. To enable the finger-piece 24 to be shifted from any one of the openings 33, 34, 35 to any other one, the openings merge into each other by an opening 38 large enough to pass the shaft 22, but smaller than the hub 32. Thus, the finger-piece 24 can be pulled forwardly out of any one of the openings 33, 34, 35 until its hub is clear of said openings, and then set in any one of the other openings.

The plate 36 is mounted on the pivot 37 so that it may shift. It is, however, normally held in its uppermost position by means of a spring 39 which is anchored in a lug 40 of the bracket 28, and draws upon a lug 41 on the plate 36. It will be observed that the result of this mounting of the plate 36 permits the finger-piece 24 to be permanently set in any one of the openings 33 or 34, and yet to be moved freely against the tension of the spring 39 along the path formed by said openings. In order to hold the finger-piece hub 32 in an opening when once set there, the shaft 22 is normally pressed rearwardly by a spring 42, which bears against the hub 43 of the rock arm 21 and against the bracket 25.

In order to limit the throw of the plate 36, it is provided with a lug 44 forming an extension thereon and slidable in an arcuate opening 45 in the bracket 28. In order to correspondingly limit the throw of the shaft 22, it passes through the slot or arcuate opening 27 in the bracket 28. In order to prevent the plate 36 from binding against the bracket

28, it may be spaced therefrom at the pivot 37 by a washer 47, and in order to prevent it being pushed rearwardly, thereby binding against the hub 32, the lug 44 may comprise an extension 48 passing through the opening 45 and overlying the outer face of the bracket 28, thus limiting the movement of the plate 36 relatively to the bracket 28.

It will be noted that when the finger-piece 24 is set at black writing position, as seen at Fig. 4, it may be pressed down to the point seen in Fig. 5, in which position it will shift the housing 13 so that the wall 14 will engage its pin 16, but the instant pressure is released, the finger-piece 24 will be drawn back with the plate 36 to the Fig. 4 position. If, however, the finger-piece 24 is set at the Fig. 6 position, it will have very little movement, because the lug 44 limits its motion in one direction, while the end of the slot 27 against which the hub 32 bears limits its motion in the other direction. If it is desired to do stenciling, the finger-piece 24 may be set at the Fig. 7 position, where it engages the opening 34, in which position neither the wall 14 nor the wall 15 of the housing 13 engages either pin 16. It will be observed that this device may be utilized for temporarily shifting to red or to stenciling position from black position by finger pressure exerted against the tension of the spring 39. This is very convenient for typing a few characters, such as a single word, or a number, in red, while leaving the ribbon mechanism set for typing in black, and so that, when the finger pressure is released, the ribbon will be automatically returned to the position for typing in black.

Owing to the length of the link 20 and to the length of the shaft 22, as well as to the flexibility of the connections of the link 20, the rotation of the shaft 22 by twisting it around the opening in the bracket 25 does not interfere with the proper operation of the various parts.

Variations may be resorted to within the scope of the invention, and portions of the improvements may be used without others.

Having thus described my invention, I claim:

1. In a typewriting machine having polychrome printing means, the combination with a link adapted to vary the color, of a shaft for operating said link, a finger-piece for shifting said shaft transversely of its axis, means for supporting the shaft to cause said shifting to rotate it, and means for detaining the shaft in its rotated position.

2. In a typewriting machine having polychrome printing means, the combination with a link adapted to vary the color, of a shaft, a finger-piece for shifting said shaft transversely of its axis, means for supporting the shaft to cause said shifting to rotate it, a holding device adapted to hold the shaft in

any one of a plurality of positions, and connections permitting the finger-piece to be moved to shift the shaft to any of its positions.

5. 3. In a typewriting machine having polychrome printing means, the combination with a link adapted to vary the color, of a shaft shiftable transversely of its axis, a plate forming a holding device for the shaft 10 adapted to hold the shaft in any one of a plurality of positions, a mounting for said plate permitting it to be moved, and a spring normally detaining the plate in one position.

4. In a typewriting machine having polychrome printing means, the combination with a link adapted to vary the color, of a shaft having an endwise movement and adapted to be rocked to shift the color-controlling link, a spring normally holding said 20 shaft at one end of its endwise movement, a hub on said shaft, and a series of openings in which said hub is adapted to be inserted to variably position the shaft to determine the nature of the color printing.

25. 5. In a typewriting machine having polychrome printing means, the combination with a link adapted to vary the color, of a shaft having an endwise movement and adapted to be rocked to shift the color-controlling link, a spring normally holding said shaft at one end of its endwise movement, a hub on said shaft, a series of openings in which said hub is adapted to be inserted to variably position the shaft to determine the nature of the color printing. 30 a pivoted plate in which said openings are formed, and a spring normally holding said plate in one position, thereby detaining the shaft at a given position.

6. In a typewriting machine having polychrome printing means, the combination with a link adapted to vary the color, of a shaft having an endwise movement and adapted to be rocked to shift the color-controlling link, a spring normally holding said shaft 40 at one end of its endwise movement, a hub on said shaft, a pivoted plate having a series of openings in which said hub is adapted to be inserted to variably position the shaft to determine the nature of the color printing, a spring normally holding said plate in one position, thereby detaining the shaft at a given position, a lug on said plate, and a bracket relatively to which said plate can swing comprising an opening adapted to 45 limit the play of said lug.

7. In a typewriting machine having polychrome printing means, the combination with a link adapted to vary the color, of a shaft having an endwise movement and 50 adapted to be rocked to shift the color-controlling link, a spring normally holding said shaft at one end of its endwise movement, a hub on said shaft, a pivoted plate having a series of openings in which said hub is adapted to be inserted to variably po-

sition the shaft to determine the nature of the color printing, a spring normally holding said plate in one position, thereby detaining the shaft at a given position, a lug on said plate, and a bracket relatively to 70 which said plate can swing comprising an opening adapted to limit the play of said lug, said bracket also comprising a second opening adapted to limit the movement of the shaft.

8. In a typewriting machine having polychrome printing means, the combination with a link adapted to vary the color, of a shaft adapted to variably position the color-controlling link, a bracket in which said shaft 80 is loosely journaled, a fork on said shaft at a point remote from said bracket, a fixed pin engaged by said fork, and a finger-piece for moving the shaft transversely of its axis and relatively to said pin to rock the shaft. 85

9. In a typewriting machine having polychrome printing means, the combination with a link adapted to vary the color, of a shaft adapted to variably position the color-controlling link, a bracket in which said shaft 90 is loosely journaled, a fork on said shaft at a point remote from said bracket, a fixed pin engaged by said fork, a finger-piece for moving the shaft transversely of its axis and relatively to said pin to rock the shaft, a 95 plate comprising an opening adapted to detain the shaft, and a spring for holding said shaft in said opening.

10. In a typewriting machine having polychrome printing means, the combination with a link adapted to vary the color, of a shaft adapted to variably position the color-controlling link, a bracket in which said shaft is loosely journaled, a fork on said shaft at a point remote from said bracket, a fixed 100 pin engaged by said fork, a finger-piece for moving the shaft transversely of its axis and relatively to said pin to rock the shaft, a pivoted plate comprising a plurality of openings adapted to detain said shaft, a spring 105 normally holding the shaft in any opening, and a spring for holding said plate at a given position. 110

11. In a typewriting machine having polychrome printing means, the combination 115 with a link adapted to vary the color, of a shaft adapted to be moved transversely to rock it to shift the color-controlling link, a spring normally holding said shaft, but adapted to permit it to be moved endwise, 120 and a plate comprising a series of openings adapted to hold the shaft when drawn thereinto by the spring.

12. In a typewriting machine having polychrome printing means, the combination 125 with a link adapted to vary the color, of a shaft adapted to be moved transversely to rock it to shift the color-controlling link, a spring normally holding said shaft, but adapted to permit it to be moved endwise, a 130

pivoted plate comprising a series of openings adapted to detain said shaft when seated therein by said spring, a spring holding said pivoted plate at a given position, 5 and a lug limiting the throw of said pivoted plate.

13. In a typewriting machine having polychrome printing means, the combination with a link adapted to vary the color, of a 10 shaft adapted to be moved transversely to rock it to shift the color-controlling link, a spring normally holding said shaft, but adapted to permit it to be moved endwise, a pivoted plate comprising a series of openings adapted to detain said shaft when seated therein by said spring, a spring holding said pivoted plate at a given position, a 15 bracket over which said pivoted plate moves and comprising an opening, and a lug in 20 said pivoted plate extending through said opening to hold the plate in the neighborhood of the bracket and to limit its throw.

14. In a typewriting machine having polychrome printing means, the combination 25 with a link adapted to vary the color, of a shaft adapted to be moved transversely to rock it to shift the color-controlling link, a spring normally holding said shaft, but adapted to permit it to be moved endwise, a 30 pivoted plate comprising a series of openings adapted to detain said shaft when seated therein by said spring, a spring holding said pivoted plate at a given position, a bracket over which said pivoted plate moves 35 and comprising an opening, and a lug in said pivoted plate extending through said opening to hold the plate in the neighborhood of the bracket and to limit its throw, said bracket also comprising an opening adapted 40 to limit the transverse movement of the shaft.

15. In a typewriting machine having polychrome printing means, the combination 45 with a link adapted to vary the color, of a shaft adapted to be moved transversely to rock it to shift the color-controlling link, a spring normally holding said shaft, but adapted to permit it to be moved endwise, a pivoted plate comprising a series of openings adapted to detain said shaft when seated therein by said spring, a spring holding said pivoted plate at a given position, a bracket over which said pivoted plate moves 50 and comprising an opening, a lug in said pivoted plate extending through said opening to hold the plate in the neighborhood of the bracket and to limit its throw, said bracket also comprising an opening adapted 55 to limit the transverse movement of the shaft, and a washer for holding the plate 60 clear of the bracket.

16. In a typewriting machine having polychrome printing means, the combination 65 of means including a member movable away from an original position to vary the

color, means for automatically returning said member to its original position when released for thereby restoring the original color, and means for locking said member away from its original position. 70

17. In a typewriting machine having polychrome printing means, the combination of means for varying the color, comprising a member movable to different positions corresponding to different colors, means including a rock-shaft for moving said member, a finger-piece for rocking the rock-shaft to vary the color, means for automatically returning the rock-shaft to its 75 original position to restore the original color 80 when the finger-piece is released, and releasable locking means for detaining the rock-shaft away from its original position, whereby the changed color condition will be maintained. 85

18. In a typewriting machine having polychrome printing means, the combination of means for varying the color, including a finger-piece movable to a plurality of different positions, means for automatically 90 returning the finger-piece to its original position when released, and releasable locking means for detaining the finger-piece away from its original position. 95

19. In a typewriting machine having polychrome printing means, the combination of means for varying the color, including a finger-piece movable to different positions corresponding to different colors, and means in control of the finger-piece comprising a 100 releasable locking catch carried by the finger-piece, a keeper with which said locking catch may have locking engagement at a plurality of different positions, said keeper being mounted for limited movement in the 105 same direction in which the catch and finger-piece move, and a spring for yieldingly maintaining said keeper at one of its limited positions of movement, whereby the finger-piece may be moved away from its original 110 position to vary the color and may automatically return to such original position when released for thereby restoring the original color, and also whereby the finger-piece may be locked away from its original position. 115

20. In a typewriting machine having polychrome printing means, the combination of means for varying the color, comprising a member movable to different positions corresponding to different colors, means including a rock-shaft for moving said member to vary the color, a finger-piece for rocking the rock-shaft, and means in control of the finger-piece comprising a releasable locking catch carried by the finger-piece, a keeper 120 with which said locking catch may have locking engagement at a plurality of different positions, said keeper being mounted for limited movement in the same direction in which the catch and finger-piece move, 125 130

and a spring for yieldingly maintaining said keeper at one of its limited positions of movement.

21. In a typewriting machine having 5 polychrome printing means, the combination of means for varying the color, including a finger-piece movable to different positions corresponding to different colors, and means in control of the finger-piece comprising a 10 pivoted keeper-plate mounted for limited movement in the same direction as the finger-piece and provided along a line of its movement with a plurality of catch-receiving openings, a releasable locking catch carried by the finger-piece to have locking engagement in 15 said openings, and a spring for yieldingly maintaining said keeper-plate at one of its limited positions of movement, whereby the keeper-plate and with it the 20 finger-piece will be automatically returned to their original positions when moved away therefrom, but providing for locking the finger-piece away from its original position when desired.
- 25 22. In a typewriting machine having polychrome printing means, the combination

of means for varying the color, comprising a member movable to different positions corresponding to different colors, means including a rock-shaft for moving said member to vary the color, a finger-piece for rocking the rock-shaft, and means in control of the finger-piece comprising a pivoted keeper-plate mounted for limited movement in the same direction as the finger-piece and 30 provided along a line of its movement with a plurality of catch-receiving openings, a releasable locking catch carried by the finger-piece to have locking engagement in 35 said openings, and a spring for yieldingly maintaining said keeper-plate at one of its limited positions of movement, whereby the keeper-plate and with it the finger-piece will be automatically returned to their original positions when moved away therefrom, 40 but providing for locking the finger-piece away from its original position when desired.

WALTER E. BARNARD.
